UNITED STATES PATENT OFFICE.

FRANK H. ALLEN, OF DONALDSONVILLE, LOUISIANA.

INKSTAND.

1,161,579.

Specification of Letters Patent. Patented Nov. 23, 1915.

Application filed August 24, 1914. Serial No. 853,259.

To all whom it may concern:

Be it known that I, FRANK H. ALLEN, a citizen of the United States, residing at Donaldsonville, in the parish of Ascension 5 and State of Louisiana, have invented certain new and useful Improvements in Inkstands; and I do hereby declare the following to be a full, clear, and exact description of the invention, such as will enable others 10 skilled in the art to which it appertains to make and use the same.

The present invention relates to inkstands, and consists more particularly in improvements in inkstands of the character wherein 15 the well or bottle is arranged to be tilted to uncover the mouth thereof and permit dipping of the pen, and which, when the same is released, will automatically return to position to cover the mouth.

20 It is an object of the present invention to provide an ink well of this type wherein the closure will be tight and effective when the stand is resting in normal position, and which will be readily and conveniently operated to uncover the opening and permit 25 insertion of the pen point.

Another object of the invention resides in providing a tilting inkstand which will be 30 constructed of few and simple parts, economical of manufacture and readily assembled and disassembled, and which, when assembled, will form an attractive article for desk use and the like.

With these and other objects in view the 35 invention consists in the novel details of construction and combinations of parts more fully hereinafter disclosed and particularly pointed out in the claim.

In the accompanying drawing forming 40 a part of this application, and in which similar reference symbols indicate corresponding parts in the several views: Figure 1 is a side elevational view of an inkstand constructed in accordance with the present 45 invention; and Fig. 2 is a central sectional view of the same.

Referring more particularly to the drawings, wherein one embodiment of the invention is illustrated, 1 designates a base, preferably 50 constructed substantially annular of a casting of iron or other suitable heavy material which will form a firm stand for supporting the various parts. The base 1 is formed with a pair of perforated ears 2 55 wherein are mounted trunnions 3, for sup-

porting the tilting platform 4. The tilting platform 4 is also preferably constructed substantially annular of some light material, advantageously aluminum, and the same is loaded or weighted at the rear thereof in 60 any suitable manner, for instance by the filling of lead 5 here shown. From the forward portion of the tilting platform 4 extends a lever 6, formed at its upper end into a hand or finger piece 7 for actuating the 65 platform, as hereinafter described.

Tilting platform 4 is arranged to receive an ink bottle or well 8, provided with a neck having an inclined mouth as shown; and, when the platform is resting in normal position the inclined mouth of the bottle is arranged to be covered by a cap 9 constructed from rubber or other suitable material. The rubber cap 9 is formed with a step 10 adapted to be received into an aperture 11, provided in the outer end of a post 12 erected on the base 1, and preferably cast therewith. A washer 13 is preferably interposed between the cap 9 and the post 11, and surrounds the stem 10, which is constructed of 80 a diameter slightly greater than that of the aperture 11, so as to frictionally hold the cap in place when the bottle is tilted.

In practice the hand piece 7 is engaged by the heel of the hand, and the lever 6 thereby depressed to tilt the platform 4 about the supporting trunnions 3, as indicated in Fig. 1, whereby the neck of the bottle will be removed from the cap 9 and permit of the dipping of the pen point therein to receive the ink in the usual manner. After the dipping operation, the hand will be removed from engagement with the piece 7, whereupon the weight 5 will return the platform 4 to the normal position, indicated in full 90 lines in Fig. 1, in which the open inclined mouth of the bottle will rest tightly against the cap 9 and be effectually closed thereby.

I have illustrated and described preferred and satisfactory constructions, but obviously 100 changes could be made in the herein described apparatus which could be used without departing from the spirit of my invention.

I claim:

As an article of manufacture an inkstand comprising a metal base having a curved upturned arm and a yielding cap carried by the head of said arm, an ink-well holder, provided with a socket adapted to receive 110

an ink bottle, trunnioned at right angles to said arm and beneath said cap, and provided with an outwardly-projecting lug adapted to engage the palm of the writer, with a 5 counterweight on the opposite side of said trunnions from said lug, and adapted to normally rock the holder to the closed position, and an ink bottle carried by said holder

and provided with a neck adapted to engage said cap, substantially as described.

In testimony whereof, I affix my signature, in presence of two witnesses.

FRANK H. ALLEN.
